TYPEWRITER CASING

Frank C. Fusco, Monroe, Norman C. Gold, New York,
and William Gold, Great Neck, N.Y., assignors to
Louis Marx & Co., Inc., New York, N.Y., a corpora-
tion of New York

Filed Apr. 11, 1969, Ser. No. 16,702

Term of patent 14 years

Int. Cl. D18—01

U.S. Cl. D64—11

FIG. 1

FIG. 2

FIG. 3

FIG. 1 is a perspective view of a typewriter casing embodying our new design;

FIG. 2 is a right side elevational view thereof; and

FIG. 3 is a rear elevational view thereof.

We claim:

The ornamental design for a typewriter casing, as shown.
